CLAIM

The ornamental design for a sound pedal, as shown and described.

DESCRIPTION

FIG. 1 is a front view of a sound pedal showing the claimed design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a top left perspective view thereof.

The dashed broken lines in the figures show portions of the sound pedal subject matter that form no part of the claimed design.
